Ara Smith's Corn Shelling
Letters Patent

The Schedule referred to in these Letters Patent and making part of the same & containing a description in the words of the said Ara Smith himself of his improvement in the machine for shelling corn.

Be it known that Ara Smith of Downington in the County of Chester and State of Pennsylvania have made an improvement in the machine for shelling corn, which is described as follows. This machine is in most respects like those in common use except that the wheel for shelling has teeth or projections on both sides as will hereafter be described. The frame (A) contains and supports the several parts of the machinery, & wheel (B) having teeth or projections cast on both sides for shelling out the corn. Springs (C) for pushing the ears of corn against the corn shelling wheel (B). A spout (D) down which the shelled corn passes. The wheel (B) is hung on an axle (E) and has a pulley (F) on one end upon which (and the pulley (G) a band passes for turning it by means of the cradle (H). The corn to be shelled is placed on an inclined plane (I) at the top of the machine, it then passes down by its own gravity to the shelling wheel where it is drawn in by the teeth and shelled, the ears flying out & the grain descending into the spout. What I claim as my invention or discovery & desire to be secured by Letters Patent, is putting teeth or projections on both sides of the wheel, instead of one side as in the common machine there by shelling twice as fast. For a further illustration of my invention I refer to the model and drawing of the same deposited in the Patent Office
